UNITED STATES PATENT OFFICE.

BERNE NADALL, OF KINGSTON-UPON-THAMES, ENGLAND, ASSIGNOR TO
THE LINOTYPE COMPANY, LIMITED, OF LONDON, ENGLAND.

DESIGN FOR A FONT OF TYPE ORNAMENTS.

SPECIFICATION forming part of Design No. 35,809, dated March 11, 1902.

Application filed January 25, 1902. Serial No. 91,290. Term of patent 14 years.

To all whom it may concern:

Be it known that I, BERNE NADALL, a citizen of the United States, residing at Kingston-upon-Thames, in the county of Surrey, England, have invented and produced a new and original Design for a Font of Type Ornaments, of which the following is a specification.

My design is clearly shown in the accompanying typographical impressions, the types composing the font being numbered 1 and 2.

The main feature of the design presented by each of the types composing the font is a conventional illustration of two three-lobed leaf-like forms the stems of which are curved in opposite directions and united by a compound curve. The lines representing the leaf-stems are single solid lines, and the irregular curve connecting said stem-lines is also a single line, which, however, is greatly increased in width at points between the lines representing the leaf-stems.

The entire design can be considered as included within a square, the leaf-like forms being arranged on one of the diagonals of said figure, while the stem-lines extend toward the

other two corners thereof. In the form numbered 1 the leaf-like forms are arranged in the upper right-hand and lower left-hand corners, while in that numbered 2 said forms are arranged in the upper left-hand and lower right-hand corners, the two forms being otherwise similar. In other words, each form is the reverse of the other.

The several type ornaments herein described are of uniform design and are adapted to be grouped in various ways to form borders and other composite typographic ornaments.

Having thus described my invention, what I claim as new, and desire to secure by Letters Patent, is—

The design for a font of type ornaments, substantially as herein shown and described.

In testimony whereof I affix my signature in presence of two witnesses.

BERNE NADALL.
